UNITED STATES PATENT OFFICE.

JEAN BARDET, OF PARIS, FRANCE, ASSIGNOR TO DOBSON, MOLLE & CO., LIMITED, OF EDINBURGH, SCOTLAND, A LIMITED COMPANY INCORPORATED UNDER THE BRITISH COMPANIES ACTS, 1862 TO 1898.

FOLDING DEVICE FOR THE MANUFACTURE OF PAPER TUBES.

1,174,039.

Specification of Letters Patent.

Patented Mar. 7, 1916.

Application filed July 17, 1913. Serial No. 779,579.

To all whom it may concern:

Be it known that I, JEAN BARDET, a citizen of the Republic of France, residing at 35 Rue d'Alsace, Paris, in the Republic of France, engineer, have invented certain new and useful Improvements in Folding Devices for the Manufacture of Paper Tubes, of which the following is a specification.

The present invention has for its object 10 to provide an improved device to be used in the manufacture of tubes and the like made from folded paper and which can particularly be employed in connection with machines for the manufacture of bags.

15 The improved device constructed according to the present invention consists substantially of two movable plates connected in such a manner that they remain always parallel in relation to one another, although 20 they may receive in a plane perpendicular to their direction two kinds of translational movements, which produce the different folds to be made in the sheet of paper arranged around these plates.

25 A form of this improved device is shown by way of example in the accompanying drawings, in which—

Figures 1 to 8 show diagrams illustrating the successive stages in the manufacture of 30 a paper tube. Fig. 9 is a diagram of the folding device. Figs. 10 and 11 are a side elevation and a plan view respectively of this folding device. Fig. 12 is an end view and Fig. 13 a transverse section on the line 35 A—A of Fig. 10. Figs. 14 and 15 show diagrammatically two different positions of the plates.

As shown in Fig. 1 the sheet of paper *a*, which is to be transformed into a tube, is at 40 first placed upon the two plates *b* and *c* arranged in the same plane. The lateral parts of the sheet projecting beyond these plates are folded under the latter by means of devices which do not form part of this invention, in such a manner that the edges, one of 45 which is gummed, are stuck together, so that the sheet forms a flat tube as shown in Fig. 2. Two presser arms *d* *e* are then caused to bear on the opposite sides of this 50 tube, near the adjacent edges of the plates *b* *c* (Fig. 3), whereupon a movement of circular translation in the direction shown by the arrows in Figs. 3 and 4, is imparted to these plates, so that each of them assumes

the previous position of the opposite plate. 55 In this manner there are formed between the two first folds 1 and 2 of the flat tube two new folds 3 and 4 at the opposite edges of the plates (Fig. 5). As the plates are then moved backward till they are again opposite one another, as shown in Fig. 6, the tube takes the form of a square prism. If the plates are at this moment moved toward each other and if at the same time, when the 60 movable fingers *f*, *g*, arranged laterally, push the sides of the tubes inwardly, said sides are 65 folded and flattened in such a manner that they form two new folds 5 and 6 (Fig. 7). The transverse section of the tube folded in this manner is shown in Fig. 8. A tube of 70 this kind is particularly adapted for the manufacture of square bags according to a process, which does not form part of this invention.

The present invention relates more particularly 75 to the arrangement of the plates *b* *c* and to their supporting and operating mechanism. Each plate is connected with a support 7, in which is arranged a slide 8 perpendicularly to the plane of this plate 80 and slides upon a guide 9, forming part of another support 10. The latter is supported by means of arms 11, 12 oscillating around fixed spindles, pins or the like 13, 14. The arms 11, 12 are parallel and are of the same 85 length, so that they form with the support 10 a linked quadrilateral. When these arms turn about their respective spindles, the supports 10 will therefore receive circular translational movements. The pivots 15, 16 of 90 such arms are arranged in such a manner that they do not meet when they come to be situated in the same plane passing through the spindles 13, 14 so that the circular translational movements of the supports may be 95 given an amplitude of 180°.

In order to turn the arms 11, 12, the sleeves carrying the latter are provided with pinions 17, gearing with toothed sectors 18, which are provided on an oscillating support 19, mechanically actuated for example by means of a cam (not shown) which acts upon an arm connected with said support. 100

Independent from the movements of circular translation which are imparted to the 105 plates *b* *c* and their supports 10, these plates can further move relatively to said supports by means of the slides 8 in a perpendicu-

lar direction. For this purpose the supports 7 are provided with pins 21 upon which levers (not shown) may act so that these supports are brought together by over-
coming the action of the springs 22.

The presser arms *d e* are arranged in such a manner upon the supports 7 that they can move laterally to the plates, so that the sheet of paper can be placed upon the latter. Said arms can further move from or toward the plates in a perpendicular direction in order to effect the desired pressing of the sheet. For this purpose the sleeves 23 carrying these arms are arranged in such a manner that they can revolve and slide on their pins 24 fixed to the supports 7; the rotation is obtained by means of a toothed sector 25 connected to the sleeve 23 and a rack 26 sliding in the support 7. The mechanism operating the rack 26 is not shown; it can be of any suitable construction. On the other hand the sliding of the sleeve on its pin is effected in one direction by means of a spring 27, arranged in the interior of the sleeve and in the other direction by means of beveled surfaces 28, 29 provided on this sleeve and the support 7. By means of these surfaces the presser arm is automatically raised when it is moved laterally and it is subjected to the action of the spring 27 as soon as it is moved parallel to the edges of the plate.

The details of construction and arrangement of the different parts described above may of course be modified without departing from the invention; so for example the presser arms *d e* may be arranged in such a manner upon the plates that they can oscillate about pins or the like parallel to these plates and perpendicular to the pins 13, 14.

Claims:

1. A folding device for the manufacture of folded paper tubes comprising two parallel axes, movable arms around such axes, supports jointed to the said arms and forming with the same a jointed lozenge, such supports having guiding parts extending perpendicularly to the plane of such axes, plates slidably mounted on such guiding

parts, the planes of these plates being parallel to the plane of the said axes, and means whereby to give to the said arms oscillatory motions of half a revolution.

2. A folding device for the manufacture of folded paper tubes comprising two parallel axes, pinions on such axes, two segments having inner teeth the center of which is located in the middle of the distance of the said axes, such segments having apertures for the passage of such pinions, and meshing with the latter, arms associated with the said pinions, supports jointed to such arms and forming with the latter a jointed lozenge and plates mounted on the said supports in such a manner as to be movable perpendicularly to their planes.

3. A folding device for the manufacture of folded paper tubes comprising a jointed lozenge two members of which swing around parallel axes located at the middle of their length, plates mounted on the two other members of the lozenge and located parallelly to the plane of the said axes, spring pressed arms mounted on such plates, the said arms being adapted to turn outwardly and inwardly as to the plates.

4. A folding device for the manufacture of folded paper tubes comprising a jointed lozenge two members of which swing around parallel axes located at the middle of their length, plates mounted on the two other members of the lozenge and located parallelly to the plane of the said axes, spring pressed arms mounted on such plates, such arms being adapted to turn outwardly and inwardly as to the plates, and inclined cam surfaces on the plates, adapted to support such arms in such a manner that they will receive an upward and downward movement when turning.

In testimony, that I claim the foregoing as my invention I have signed my name in presence of two subscribing witnesses.

JEAN BARDET.
